UNITED STATES PATENT OFFICE.

ARTHUR W. HOLMES, OF VEEDERSBURG, DONALD E. JAQUES, OF THORNTOWN, AND HENRY B. COATS, OF VEEDERSBURG, INDIANA.

PORTRABLE CLEANER.

Application filed June 25, 1926. Serial No. 118,468.

This invention relates to means for cleaning trays of crates or cages positioned in parallel but separated relation.

The chief object of the invention consists in providing a cleaner for the trays of cages which is readily passable between parallel and separated cages having exterior projecting feed troughs and with a minimum of clearance.

The chief feature of the invention consists in constructing the cleaning device such that it is readily passable between the separated cages for cleaning the trays thereof and clear the projecting feed troughs supported by said cages in the aisles resultant therebetween.

The full nature of the invention will be understood from the accompanying drawings and the following description and claim.

20 In the drawings Fig. 1 is an end elevational view of the cleaner positioned in the aisle between two portable cages. Fig. 2 is a side elevational view of the cleaner.

In the drawings there is illustrated a pair 25 of cages 10 which are portable upon the supporting wheel means 11 and which are divided into superposed compartments 12.

The cages 10 are of a character to receive chickens and the like. In collection depots 30 the chickens are brought in by the producers and are transferred to the compartments 12 of the cages 10 and held therein until such time as they are to be shipped or dressed. During the holding time it is necessary that 35 the chickens be fed and watered and for that purpose the troughs 13 supported on the brackets 14 are provided. To facilitate the movement of the cages while in the holding relation the same are made portable as 40 described, and when loaded or filled with chickens the several cages are arranged in succession forming an aisle between adjacent cages with the feeding and watering troughs projecting into the aisle and in 45 superposed relation as shown. In order to continually use the cages without excessive cleaning and sterilization each compartment is provided with a tray indicated by the dotted lines 15 in the several figures and said 50 tray is of a character whereby it is readily removed from the cage 10 with the débris and waste thereon and is receivable by the cleaner for cleaning purposes. After being cleaned the tray is returned to the cage in a

cleaned and sterilized condition and the cage 55 is thereupon ready for use.

In establishments of the character described, floor space is not always in abundance, and therefore the aisles between the cages are reduced to a minimum. The cleaning device shown herein is of a character that it may pass down the aisle between adjacent cages with sufficient clearance and yet be of a size sufficient to accommodate and clean the trays, the width thereof being less 65 than the aisle clearance but greater than the aisle projecting feeding and water trough clearance. Other features of the invention reside in the cleaner per se.

In the drawings 20 indicates a relatively 70 narrow cleaner body portion or compartment and upwardly and laterally inclined portions 21 and side walls extending upwardly so as to form a wider portion as at 22. Thus, the side walls and inclined portions 75 form the mouth of the hopper arrangement discharging into the narrow portion 20. The narrow portion 20 has one end closed by the end gate 23 having the handle 24 thereon and having the locking pins or trunnions 25 80 and 26 cooperating with the supporting members 27 and 28, respectively. Suitable wheel means 30 provide for the portable character of the cleaner. Supported by the upper part of the body portion are a pair 85 of frames 31 between which is pivotally mounted the tubular standard 32 as at 33 in the brackets 34. Said tubular standard terminates in a reel support 35 carrying an electric cable 36, one end of which terminates in a connection plug 37 and the opposite end of which after passing through the tubular standard 32 is extended as at 38 to the motor or source of power 39. Within the wider portion 22 a brush 40 extends substantially across from one side to the opposite side thereof and the shaft 41 thereof is provided with wheel means associated with which is the endless driving belt 142 driven by the motor through suitable wheel means. 100 Any type of preferred or desired driving connection may be provided. The brush 40 is adapted to clean the tray 41 when passed therebeneath and through the path of the bristles by engaging said tray when the tray support 42 is reciprocating to and fro longitudinally of the machine by means of the handles 43.

In order to sterilize the tray either before and preferably also after cleaning by the brush, there is provided a disinfectant containing tank 44 having the filling opening 5 therein and having the discharge line 46 terminating in a nozzle 47 including a valve 48 and spray portion 49. Rigidly mounted by the disinfectant tank supporting framework is a pump or pressure device 50 having the rod 51 terminating in the handle 52. This may consist of the device such as a bicycle pump arrangement and serves to discharge disinfectant which may be liquid ammonia or the like from tank 44. In the cleaning operation brush 40 discharges the waste and débris from the tray 41 into the bottom of the body where it is collected. The body includes the inclined bottom 52 which is of assistance in removing said waste and débris through the closure 23. To facilitate movement of the cleaning device the handles 54 are provided and as shown in Fig. 1, either handle is adapted to serve as a support for the spraying nozzle of the disinfectant attachment. In order to insure operation and security thereof, suitable means such as the tines 55 are provided which are slidably supported in brackets 56 at the forward end of the body and are connected by 30 a transverse member 57, in turn connected

to the actuating member 58. This is elevated and lowered by a lever 59 pivotally supported at 60 and arranged in such a manner that access is had to the opening 61 in the end of the cleaning device to permit the tray to pass beneath the cleaning brush 40 only when the tines are in the anchoring position for anchoring the device against movement. 35

As shown clearly in Fig. 1, the distance required between cages 10 is reduced to a minimum since the tray cleaning portion is arranged to pass between superposed projecting troughs. 40

The invention claimed is:

A cleaning device for poultry crate pens 45 and the like including a lower compartment and above it a wider compartment, communicating therewith and with an opening to receive the crate pans to be cleaned, wheels for supporting said lower compartment to render the device portable, and means mounted in said upper wider compartment for cleaning the crate pans when placed therein and discharging the waste into the lower compartment. 50 55

In witness whereof, we have hereunto affixed our signatures.

ARTHUR W. HOLMES.
